UNITED STATES PATENT OFFICE.

THOMAS HAFFER, OF WILLIAMSPORT, PENNSYLVANIA, ASSIGNOR TO TARENTUM MANUFACTURING COMPANY, A CORPORATION OF PENNSYLVANIA.

SHADE AND CURTAIN-POLE FIXTURE.

933,249.

Specification of Letters Patent. Patented Sept. 7, 1909.

Application filed December 16, 1908. Serial No. 467,778.

To all whom it may concern:

Be it known that I, THOMAS HAFFER, a citizen of the United States, residing at Williamsport, in the county of Lycoming and State of Pennsylvania, have invented certain new and useful Improvements in Shade and Curtain-Pole Fixtures; and I do hereby declare the following to be a full, clear, and exact description of the invention, such as will enable others skilled in the art to which it appertains to make and use the same.

My invention relates to shade and curtain fixtures for windows and has for its object to provide a fixture capable of quick attachment to window-frames of different widths and arranged at the same time to support the shade-roller and curtain-pole, the entire fixture being quickly put in place and easily removable as it does not require nails, screws or other permanent fastenings.

It is sometimes necessary or desirable to suspend the curtain at such a distance from the window as to clear a wide window sill, radiator, or other projection, and to arrange the curtain at such a distance from the shade-roller, that the shade in rolling up or down will not interfere with or entangle the curtain or the projecting hem thereof, besides which the projecting of the curtain permits it to be draped artistically or to suit the taste of the housewife. This may be accomplished by means of my improved fixture, in which I provide means whereby the distance of the curtain from the window may be varied to suit local conditions.

Referring now to the accompanying sheet of drawings in which like characters refer to like parts throughout the views:—Figure 1 is a front elevation of the upper part of a window-frame showing a pair of my improved fixtures in place. Fig. 2 is a top plan view of the same, a shade-roller and a curtain-pole being shown in position. Fig. 3 is a perspective view of one of my fixtures, showing a portion of the spring attached to the end and the shade-roller support and curtain-pole support in position. Fig. 4 is a similar view of the mate of the fixture shown in Fig. 3, the spring and the curtain-pole support being omitted. Fig. 5 is a perspective view showing the curtain-pole supports, one being right-handed and the other left-handed. Fig. 6 is a similar view of the shade-roller support.

In the drawings 1 indicates the main bracket portions of my improved fixture, two of which are joined by a spring 2, which holds them in position on the window-frame 3. The spring 2 is attached at either end to an eye 4 formed in the inner end of the arm 5 of the fixture.

The body part of the fixture in the form shown in Figs. 3 and 4, consists of three integral arms, of which 5 and 6 have their axes horizontal and 7 has its axis vertical. The arms 5 and 7 lie as closely as possible to the window-frame, and 6 stands out approximately perpendicular to the same. Arm 7 is provided with tangs 8 formed integral with the same by punching or its equivalent. These tangs are forced into the side of the wooden-frame to support the weight borne by the fixture. The spring 2 by its action keeps the tangs embedded in the wood. The outstanding arm 6 is provided with a number of holes which consist of a slotted portion 9 and an enlarged portion 10. The outer end 11 of this arm is bent at right angles to the main part and provided with a notch 12 to form a support for the curtain-pole holder 13. The edges of the arm 5 are bent over to form lips 14 which hold the shade-roller support 15 in place, but permit it to slide in a horizontal direction.

As shown best in Fig. 6, the shade-roller support is formed in one piece, the outstanding part 16 being provided with an oval hole 17 so shaped as to receive the projection on either end of the roller. The part which is inserted between the lips 14 of the bracket is arched as at 18 to give it a spring action to prevent displacement while in use. The curtain-pole support 13 is formed with a hooked portion 19 to hold the pole and has its inner end reduced in cross section as at 20. The end 21 of this reduced portion is bent to the side approximately at right angles and slotted at 22. To mount the holder, the outer end is raised and the end 21 inserted in the enlarged hole 10 in the arm 6. The holder is then revolved until it rests in the notch 12 and then pulled out, the slot 22 on the holder permitting it to slide into the slotted hole 9 on arm 6 so as to hold it in position.

The main brackets of my invention and the shade-roller support adjustably mounted therein, are preferably made of sheet

metal stamped, pressed and punched into the formis shown.

Although I have shown and described my improvements in considerable detail, I do not wish to be limited to the exact and specific details shown and described, but may use such substitutions, modifications or equivalents thereof, as are embraced within the scope of my invention or as pointed out in the claims.

Having thus described my invention, what I claim and desire to secure by Letters Patent is:

1. In a fixture of the class described, a bracket which consists of an arm adapted to lie in a plane substantially parallel with the plane of the front surface of a window-frame, an arm adapted to contact with the side of said frame, and an outstanding arm, all integral, the end of the outstanding arm being bent to form a support for a curtain-pole holder.

2. In a fixture of the class described, a bracket which consists of an arm adapted to lie in a plane substantially parallel with the plane of the front surface of a window-frame, an arm adapted to contact with the side of said frame, and an outstanding arm, all integral, the end of the outstanding arm being bent and notched to form a support for a curtain-pole holder.

3. In a fixture of the class described, a bracket which consists of an arm adapted to lie in a plane substantially parallel with the plane of the front surface of a window-frame, an arm adapted to contact with the side of said frame, tangs projecting from the inner surface of said latter arm, and an

outstanding arm, all integral, the end of the outstanding arm being bent and notched to form a support for a curtain-pole holder.

4. In a fixture of the class described, a bracket which consists of an arm adapted to lie in a plane substantially parallel with the plane of the front surface of a window-frame, an arm adapted to contact with the side of said frame, tangs projecting from the inner surface of said latter arm, and an outstanding arm provided with holes consisting of a slotted portion and an enlarged portion, all integral, the end of the outstanding arm being bent and notched to form a support for a curtain-pole holder.

5. The combination of a pair of brackets and a spring, said brackets each adapted to engage the side of a window-frame, and each consisting of a member adapted to lie in a plane substantially parallel with the front surface of the window, and having a shade-roller support adjustably mounted therein, another member at substantially right angles thereto, provided with integral tangs on its inner surface to engage the sides of the window-frame, and an outstanding member having its outer end bent and notched to form a support for a curtain-pole holder, said members being integral, said brackets being held in place by said spring connecting their adjacent ends.

In testimony whereof I hereto affix my signature in the presence of two witnesses.

THOMAS HAVER.
